UNITED STATES PATENT OFFICE.

LOUIS ALFRED WHITE, OF BROOKLYN, NEW YORK.

CONTROLLER.

1,311,784.

Specification of Letters Patent.

Patented July 29, 1919.

Application filed December 18, 1914. Serial No. 877,994.

To all whom it may concern:

Be it known that I, LOUIS A. WHITE, a citizen of the United States, residing at Brooklyn, in the county of Kings and State 5 of New York, have invented certain new and useful improvements in Controllers, of which the following is a specification, reference being had therein to the accompanying drawing.

10 This invention relates to controllers, more specifically to electrical controllers and has for its object the provision of a device of this character which will be capable of a wide variety of uses as will appeal to persons skilled in the various arts to which the invention relates, I having conceived the improvements as suitable for service in connection with the control of valves, that is, the opening and closing thereof, the control 15 of speed changing mechanism, and the control of steering rudders on ships, etc.

The invention in its broad aspects embraces the combination of regulating mechanism, setting mechanism, and actuating mechanism, the regulator being designed to set up motion in the various parts to obtain the actuation desired, as determined by the adjustment thereof; the setting mechanism being designed to insure the actuation in 20 a forward or retrograde manner, as also determined by the position of the controlling mechanism, and the actuating mechanism being designed to shift the part or parts to be affected by the controller.

25 The parts referred to include many improved features in detail of construction and association of parts, as will be understood from the specific description herein-after contained, when read in connection 30 with the accompanying drawings forming part hereof, and wherein the preferred embodiment of said invention is illustrated, for the purpose of facilitating a disclosure of the invention.

35 In the drawings,

Figure 1 is a horizontal sectional view, parts being shown in elevation;

Fig. 2 is a side view, a part of the casing being removed to show the devices on the 40 interior thereof;

Fig. 3 is a vertical sectional view;

Fig. 4 is a similar view taken at right angles to Fig. 3, and,

Fig. 5 is a diagrammatic view enabling 45 the following of the circuits of operation

through the combination constituted by the regular setting and actuating mechanisms.

Referring more specifically to the drawings, wherein like reference characters designate corresponding parts in the several views, A represents the regulating mechanism, B the setting mechanism, and C the actuating mechanism. I will refer to the reverse setting mechanism first, so that the purpose of the combination may more readily appear, and be kept in mind, during the later consideration of the actual cooperation of elements to accomplish such purposes. D represents a fixed frame or support constituting a part of the structure 60 adapted to be controlled and upon which the setting and actuating mechanisms are adapted to be rigidly supported so as to couple by a flexible cable, represented at E to the regulating mechanism, which may 65 either be mounted upon some supporting structure or may be of a relatively portable type to be held in the hand of the operator and to be carried and manipulated by the operator while permitting freedom of movement of the latter from place to place within the limits circumscribed by the length of the cable E, which, of course would be advantageous in connection with the operation of a boat rudder, speed control of mechanical 70 piano players or similar instruments, and in other cases as may hereafter appear. F indicates a rack bar to be moved back and forth by a pinion G, said rack bar F being 75 intended to be secured to the part to be ultimately affected by the controller, for example, the end of the bar may be connected to a small friction disk adapted to be 80 shifted over the face of a larger disk, as is frequently encountered in speed control 85 devices, or which may be connected to a valve adapted to be opened and closed to different extents to control pneumatic motors; or it may be connected with a crank 90 or offset arm on a pivoted rudder, all of 95 which will be obvious to persons of mechanical skill, and need not be specially shown herein, in view of the fact that my invention has especial reference to the controller *per se*.

100 The mechanism employed by me is intended to secure the different extents of movement of the rack bar F, in either a forward or reverse direction, as might be in keeping with the desire of the operator, and 110

this result is accomplished through the medium of the following instrumentalities, to wit:

H is a rotatable shaft mounted in suitable bearings *h* of the framework D, such shaft carrying at a point approximately centrally thereof, and in the space between the standards *h*, a plate armature I fixed to rotate with the shaft H.

10 On opposite sides of the armature I and separated therefrom to normally leave substantial spaces therebetween, as shown, I mount upon the shaft H a pair of magnets J, each magnet having attached to the outer 15 face thereof (which is the face opposite to that adjacent to the armature I) ratchet wheels K and L, the teeth of which are disposed in opposite directions. The magnets J are loosely mounted upon the shaft 20 H, so that they cannot rotate with the latter until one or the other of the magnets is energized and attracts the armature I, the latter being splined upon the shaft H, as at 25 *i*, to permit a slight sliding movement,— when the rotation of the energized magnet will, through the medium of the armature, turn the shaft H and pinion G in a forward or reverse direction, dependent upon the 30 particular magnet energized at the time in question, the ratchet wheel K being intended to operate its magnet in a forward direction and the ratchet wheel L to operate its magnet in a reverse direction. The armature is roughened on its opposite faces and the adjacent faces of the magnets are correspondingly roughened to obtain an interlocking of these faces when the armature is attracted by either of the magnets so as to insure proper rotation of the shaft and the part to 35 be moved thereby.

The setting mechanism thus far defined is furnished, as will be obvious, to place the parts in the position to be actuated either in the forward or reverse direction to which I 40 have alluded, and after such setting the actuation or rotation of the means referred to is obtained as follows: A pair of pawls M pivoted at *m* to a bar *m'* constitutes means for turning the ratchet wheels, one of these 45 pawls being mounted beneath the ratchet wheel K, and the other above the ratchet wheel L, and being held in engagement with their respective teeth by a spring *m*² backing up the pawls as illustrated, resilient metallic dogs *m*³ holding the pawls against reverse movements, so that the turning of one ratchet wheel and its magnet will have no influence on, or be impeded by, the other ratchet wheel and its magnet. The bars *m'* are 50 mounted for longitudinal sliding movement in bearings *d* of the framework D, and the reciprocation of the bars to effect the actuation of the ratchet wheels by their respective pawls is obtained by means of a pair of 55 solenoid magnets N, each furnished with an

armature O secured to its bar *m'* and adapted to be attracted as the respective magnets are energized, as will be readily appreciated, being thrust in the opposite direction by 60 springs o.

Of course, the extent of movement imparted to the rack bar F under the influence of the pinion G is dependent upon the rotation of the ratchet wheel K or L, and to give the same the extent of movement desired in any one direction, the same is accomplished by a quick succession of operations of the armature O and pawl in consonance with the corresponding successive 70 separate energizations of the magnet. To 75 secure the desired number of movements of the pawl, the magnets are energized by means of the regulating mechanism constituting the portion A of my apparatus, it being understood, as will more fully herein- 80 after appear, that only one of the magnets N is operated at a given time.

Referring now to the regulating mechanism, P represents a suitable supporting base on which is an insulated housing *p*, the 85 base being adapted to be secured in place by means of the apertured flanges *p'*, or remain unattached for retention in the hands of the operator, as may be found expedient, or in keeping with the whim or desire of the user.

On the base P and rotatably mounted in the housing is a shaft *q* supporting a commutator Q divided peripherally, into a plurality of exposed contact segments *q'* of copper by insulating inserts *q*² operatively 90 associated with a spring pressed commutator brush R mounted on the base P maintaining a constant surface contact with the commutator, one end of the commutator shaft being provided with a pinion S constantly 95 intermeshing with a regulator rack s, the latter passing through the ends of the casing *p* and being adapted to be moved back and forth by the finger of the operator to turn the pinion and commutator,—suitable indicator characters being employed if desired to assist in the movement of the rack to the extent desired. Against one face of the commutator (the face opposite to that adjoining which the pinion S is mounted) a 100 friction disk T, loosely mounted upon the shaft *q*, is pressed by an adjustable spring *t*, the pressure of which is adjusted by a nut *t'* on a complementary threaded portion of the shaft *q*, and the face of the disk T being 105 surfaced with leather or equivalent material *t*² so as to insure turning of the disk when the commutator is turned by means of its rack and pinion, and until the disk is otherwise retarded, as will now be set forth.

U is a switch carrier-member attached to the insulated disk T and bearing a contact point or brush *u* normally thrust toward the disk by a spring V, the contact point or brush *u* being arranged to engage either of 110

the corresponding contact plates W, W' upon the turning of the disk in the directions indicated by the full and dotted arrows. The end of the switch carrier member U also operates as a contact closure to alternately press the spring contact members X, X' into engagement with the opposite ends of a common contact device Y.

The contact members W, W' are provided 10 with shoulders w, so that when the friction disk T is in position to have the switch carrier member U occupy its midway or neutral position, said disk by reason of its frictional surface engagement with the commutator 15 will be initially turned with the commutator under the power of the rack s and pinion S until the contact carrier is engaged with one of the shoulders w when the contacts u and W or W' will be electrically engaged. Then 20 by reason of the stoppage of the disk by the shoulder referred to, the commutator may continue its rotation independently of the friction disk to alternately close and break the circuit through the medium of its exposed peripheral portions and the commutator brush R.

Z is a battery for furnishing the source of power for operating the setting and actuating mechanisms, the opposite leads from the 30 battery being indicated by the numerals 1 and 2. The former leads to the brush R and branches at 3 to connect with the contact member Y, which when closed, as shown, permits the current to flow through the 35 switch contact X and wire 4 to a brush 5 adapted to engage a commutator ring 6 on one of the magnets J. From the magnet the current flows through the shaft H and wire 2 back to the battery. This circuit is indicated by the full line, single arrows in the 40 diagram, and results in the energization of the magnet J to draw the armature I thereagainst, and thereby couple the shaft H and magnet to rotate together. At the same time 45 the circuit is completed along the line indicated by the full line double arrows through the wire 1 and branch 7 to the brush R through the commutator Q, wire 8 (Fig. 3) leading from the latter to the shaft g, and 50 wire 9 (Fig. 5) electrically connecting the shaft with the spring actuated contact V—u, (Figs. 4, 5,) from which the current flows through the contact plate W and wire 10 leading therefrom to one of the magnets N, 55 and from the magnet through the wire 11 back to the battery, thus effecting the energization of the magnet N, resulting in the attraction of its armature O and the actuation of the ratchet wheel K by the movement of 60 the pawl M.

The movement of the contact carrier U to the position indicated in dotted lines closes the contact member Y and X' together, under which conditions the current will follow 65 the circuit indicated by the single dotted

line arrows to energize the opposite magnet J and set the setting mechanism in its reverse position, at the same time causing the current to travel the line of the dotted double line arrows to energize the other magnet 70 N and effect actuation of the ratchet wheel L to rotate the shaft H in the reverse direction.

The wiring between the regulating mechanism A and the setting and actuating mechanisms designated respectively B and C are in practice incorporated in a cable E of any length desired so that, as previously stated, the regulating mechanism may be removably mounted in place through the medium of its 75 base so as to constitute a permanent fixture, or may be a portable element, as particularly shown here, adapted to be held in the hand of the operator occupying any convenient place within the region determined by the 80 length of the cable.

From the foregoing description, it is believed that the operation of my improved apparatus will be clear, but it is perhaps well to observe that the finger rack bar s 90 being pushed in either one or the other direction will correspondingly rotate the pinion S of the regulating mechanism, which in turn will partially revolve the commutator Q and friction disk T to effect a closing of 95 the circuit by engagement of the contact device Y with the appropriate spring contact X or X', which as before set forth, will energize the corresponding magnet J and attract the armature I to set the mechanism 100 B to rotate the pinion G either forwardly or backwardly as the case may be. The operation just set forth also through the medium of the spring contact u in engagement with the contact plate W or W', closes the circuit 105 of one of the magnets N retracting the armature thereof and effecting the turning of the corresponding ratchet wheel K or L. The further rotation of the commutator Q, is independent of the friction disk, the movement 110 of the latter having been stopped by the shoulder portion w, and such further movement of the commutator is intended to determine the number of actuations of the magnet N to correspondingly effect the movement 115 of the rack bar F, as desired, the operation being rapidly repeated so long as the regulating finger rack bar s is moved to successively make and break the current through the medium of the commutator Q 120 and the contact R.

A reverse movement of the finger rack bar will initially move the contact carrier u with the commutator over into engagement with the opposite contact plate which, 125 in the instance shown in the drawing, is the contact plate W' which, as hereinbefore brought out, will bring into play the other magnets J and N, and permit the reverse movement of the opposite ratchet (that 130

shown being the ratchet wheel L) so that the rack bar will be moved in the direction opposite to its first mentioned movement.

As stated in the fore part of this specification, the field of service of a controller such as I have disclosed is a wide one, and its usefulness will appear in many cases where an electric controller may be advantageously employed, it simply being borne 10 in mind that the rack bar F moves the immediately controlled device,—as a rudder, valve, gear changer, etc. etc.,—in a forward direction when the setting mechanism is in one position, and in a backward direction 15 when the setting mechanism occupies its alternate position.

While I have herein disclosed one special embodiment of my invention, it is to be understood that the invention is susceptible of 20 embodiment in many other forms and devices, and that changes and substitution of parts, and combinations thereof as herein outlined may be made, as will be in keeping with the hereto appended claims, without 25 departing from the spirit of the invention.

I claim:

1. A controller of the character described comprising controlled reversible setting means, similar controlled actuating mechanism, and means for closing the circuits leading to the setting and actuating mechanisms comprising a rotatable commutator and a frictionally held contact shifter carried thereby, the commutator having 30 movement independently of the disk after 35 the latter has been engaged for effecting subsequent operation of the actuating mechanism.

2. A controller of the character described 40 comprising setting mechanism including separate magnets operatively associated with a driven member, and means also associated with said member for effecting operation of the same in reverse directions dependent 45 upon the energization of the magnets, said last mentioned means including a part adapted to be influenced by the magnets, and actuating parts operating in opposite directions, in combination with separate 50 magnet controlled devices for operating said actuating parts, and regulating means for the various magnets comprising a shiftable contact carrier adapted to close a circuit through one pair of magnets and having 55 a projecting part adapted to close the circuit through the other pair of magnets, substantially as and for the purpose described.

3. A controller of the character described 60 comprising setting mechanism including separate magnets operatively associated with a driven member, and regulating means for the various magnets and for effecting successive energizations of the operating magnets for the actuating parts comprising

a commutator and a contact shifter frictionally carried thereby permitting the commutator to continue its movement when the contact shifter is engaged with a stop therefor.

4. A controller of the character described comprising setting mechanism including separate magnets operatively associated with a driven member, and regulating means for the various magnets and for effecting successive energizations of the operating magnets for the actuating parts comprising a rotatable commutator and a contact shifter frictionally carried thereby permitting the commutator to continue its rotation when the contact shifter is engaged with a stop therefor. 70

5. A controller of the character described comprising setting mechanism including separate magnets operatively associated with a driven member, regulating means for the various magnets and for effecting successive energizations of the operating magnets for the actuating parts comprising a commutator and a contact shifter frictionally carried thereby permitting the commutator to continue its movement when the contact shifter is engaged with a suitable stop co-operating therewith, and a manually actuatable device for moving the commutator. 80 90

6. In a controller of the character described, reversible setting mechanism, actuating mechanism, and means for initially operating the setting mechanism and for subsequently operating the actuating mechanism, said last mentioned means including regulating mechanism adapted on its initial movement to carry a contact closing device for operating the setting mechanism and in its subsequent movement to operate the actuating mechanism. 100

7. In a controller of the character described, setting mechanism, actuating mechanism, and means for initially operating the setting mechanism and for subsequently operating the actuating mechanism, said last mentioned means including regulating mechanism adapted in its initial movement to carry a contact closing device and in its subsequent movement to be released from said closing device, said regulating mechanism including a commutator and coacting brush, and a circuit closer associated with the commutator and brush adapted in the initial relative movement thereof to be shifted 110 thereby, but permitting continuous relative movement independently of the contact closer, substantially as described. 115

8. In a controller of the character described, setting mechanism, actuating mechanism, and means for initially operating the setting mechanism and for subsequently operating the actuating mechanism, said last mentioned means including regulating mechanism adapted in its initial movement to 120 130

carry a contact closing device and in its subsequent movement to be released from said closing device, said regulating mechanism including a commutator and coacting brush, and a circuit closer associated with the commutator and brush adapted in the initial relative movement thereof to be shifted thereby, but permitting continuous relative movement independently of the con-

tact closer, in combination with manually 10 actuatable means for securing the relative movement of the commutator and its brush.

In testimony whereof I hereunto affix my signature in the presence of two witnesses.

LOUIS ALFRED WHITE.
